ELECTRONIC OSCILLATOR AND MULTIPLIER

Robert Rhea Goodrich, 2nd, Camden, N. J., assignor to Radio Corporation of America, a corporation of Delaware

Application March 28, 1936, Serial No. 71,513

12 Claims. (Cl. 250—36)

My invention relates to electronic oscillators and multipliers. More specifically, my invention is an electronic discharge device which depends for its oscillation on two sources of electrons: one, a thermionic source of primary electrons; the other, surfaces emitting secondary electrons upon electronic bombardment.

Electronic oscillators and multipliers which depend solely on secondary emission offer advantages such as: high amplification, and quiet operation. However, the operation of such devices is not without disadvantages. The electronic stream must be initially started. There are two accepted theories accounting for the initial triggering of the electronic stream. In one theory it is assumed that a photo-emission of electrons accounts for the triggering effect. In the other theory, it is assumed that a small amount of residual gas is ionized thereby starting the electronic movement.

If the photo-emissive type of electrode surfaces are employed, these surfaces may be highly secondarily emissive and will operate under a high vacuum (10^{-5} mm. of mercury) but gas is apt to be driven out of the electrodes. This gas will ruin the photo-emissive properties of the electrodes. Thereafter, the triggering effects must come from the ionization of the gas. But the ionization of the gas is a critical matter depending upon pressure. It has been found that critical gas pressures are difficult to maintain. This is due to clean-up of the gas by the electrodes themselves.

One of the objects of my invention is to combine the secondary electron emissive electrode and a thermionic electron emitter in an electronic device. Another object is to supply a triggering device for a secondary electron emitter. A still further object is the embodiment of an electronic emitter whose surface is treated to be highly emissive of electrons upon bombardment by primary electrons and the inclusion of a thermionic emitter in the plane of said surface whereby the electronic device may operate substantially independent of critical gas pressure or photo-emissive electrode surfaces. An additional object is to combine a secondary electron emissive element and an electronic gun electrode within a high evacuated envelope substantially free from ionizable gas.

Figure I is a schematic illustration showing an embodiment of my invention in an electronic oscillator.

Fig. II represents a modification of the elec-

tronic device of Fig. I employing a filament type cathode.

Fig. III is a diagram showing my invention applied to a push pull oscillator, and

Fig. IV is an enlarged sectional view of a unipotential cathode which may be embodied in my invention.

In Fig. I within a highly evacuated envelope 1 are included a pair of electrodes 3, 5, and an accelerating anode 7. Each of these electrodes is 10 suitably supported by wires 9, 11, 13, which may also act as the lead-in conductors. The surfaces of the pair of disc shape electrodes 3, 5, are preferably treated with beryllium oxide, or the like, to make them highly electron emissive. The accelerating anode may be formed of a circular band of metal which is preferably divided, as shown, by a strip 15.

An electronic gun, or unipotential cathode 17 is inserted through a suitable orifice 19 in one of the electrodes 5. The end surface of the unipotential cathode 5 is preferably flush with the inner surface 21 of the electrode. The cathode 17 is heated by a heater wire 23 in the conventional manner. One of the heater leads may be connected within the envelope to the supporting conductor 13. The other heater lead is connected to the cathode heater battery 25 which is joined to the conductor 13. The unipotential cathode 17 is likewise connected to the conductor 13 or 30 electrode 5.

A tunable circuit 27 comprising an inductor 29 and capacitor 31 is connected between the pairs of electrodes 3, 5. The positive terminal of a biasing battery 33 is connected by means of conductor 11 to the accelerating anode 7. The negative terminal of this battery 33 is connected to a tap 35 intermediate the ends of the inductor 29. A magnetic field, supplied by a permanent or electromagnet 30, is arranged so that its lines of force are substantially coaxial with the axis of 40 the accelerating anode.

After the cathode has been heated, primary electrons are emitted, these primary electrons are accelerated by the anode 7, and some of these 45 electrons strike the electrode 3 at high velocity. The striking electrons thus lose their energy and liberate secondary electrons. At the same time a transient current in the tuned circuit sets up an alternating current. This current alternately 50 makes one of the pair of electrodes 3, 5 positive and negative with respect to the other electrode. The secondary electrons from the electrode 3 are attracted to the momentarily positive electrode 5, and upon impinging on this electrode 5 more sec- 55

ondary electrons are emitted. These electrons, in turn, are impinged on the then momentarily positive electrode 3. These cycles continue with ever increasing numbers of electrons until the space charge and collection of electrons by the accelerating anode limit the numbers of electrons travelling back and forth between the electrodes 3, 5.

From the foregoing description, it would seem that the cathode could be de-energized once the electronic cycles were started. This is true in many electronic tubes, but I prefer to maintain the cathode heated. The heated cathode, although it may only supply a few of the total number of electrons, acts as a stabilizing element, permits more uniform manufacture of tubes, and more stable operation.

In Fig. II a modification of my invention, employing a filament type cathode, is illustrated. The evacuated envelope 41 is arranged with a cylindrical anode 43 supported by a conductor 45. A cylindrical electrode 47 surrounds the anode 43 and is concentrically mounted with respect thereto by conductors 46. The inner surface 49 of the electrode 47 is treated to render it highly electron emissive. A V shape opening 51 is pierced in the electrode 47. A pair of conductive leads 53 are mounted so that their ends terminate within the V without contacting the electrode 47. A suitable electron emitter filament is conductively arranged between the leads 53 and is supported at its center by a wire 55 which is attached to the electrode 47.

The filament is arranged to lie substantially in the plane of the surface of the electrode 47. The filament is heated by a battery 57. A solenoid 59 is arranged to surround the envelope 41. The solenoid is energized by a battery 61.

The conductor 45 which supports the anode is connected to the positive terminal of battery 63. The negative terminal of the battery is joined to one terminal of a tuned circuit 65 which is composed of an inductor 67 and a variable capacitor 69. The other terminal of the tuned circuit is connected to the conductors 46 which in turn connect to the electrode 47.

The operation of this embodiment of my invention is somewhat different from the circuit of Fig. I. In the present case the filament emits primary electrons. These primary electrons, under the influence of the magnetic field travel outwardly but follow a curved path approaching the anode and returning at high velocity to the surface of the emissive electrode 47. The primary electrons impinging on the emissive electrode cause the emission of increasing numbers of secondary electrons. A transient current in the tuned circuit 65 establishes oscillatory currents which are sustained by and at the same time aid the electronic movements as previously described. Although the filament may be de-energized I prefer to maintain it in the heated condition in which state it aids the operation of the oscillator.

In Fig. III a schematic diagram illustrates an embodiment of my invention applied to a push-pull magnetron oscillator. A pair of accelerating anodes 71, 73 are suitably supported within an evacuated envelope 75. Within these anodes 71, 73 are concentrically mounted a pair of electrodes 77, 79 which are supported by conducting wires 81. The outer surfaces of the electrodes 77, 79 are treated to render them high electron emissive. A pair of unipotential cathodes 83, 85 are inserted through orifices 87, 89 with the elec-

trodes 77, 79 from within the electrodes. The end surfaces of the cathodes 83, 85 are preferably in the plane of the emissive surfaces of the electrodes 77, 79. The heaters 91, 93 for the cathodes 83, 85 may be connected in series or parallel and are preferably connected to the electrodes. The cathodes 83, 85 are connected to the electrodes 77, 79.

A solenoid 95 or other suitable source of magnetic field is used to create a field whose lines of force are substantially coaxial with respect to the longitudinal axis of the several electrodes. The solenoid is energized by a battery 97. This same battery may be used to energize the heaters 91, 93. The accelerating anodes 71, 73 are respectively connected to the terminals of a tunable circuit 99 which is comprised of an inductor 101 and a capacitor 103. A battery 105 is connected between the junction of the secondary emissive electrodes 77-79 and a tap 107 intermediate the ends of the inductor 101. The battery is poled to make the anodes positive with respect to the secondary emissive electrodes.

The operation of the circuit of Fig. III is substantially the same as the circuit of Fig. II. The push-pull oscillator is so well known to those skilled in the art that further description is not required. It should be understood that the unipotential or electron gun type of cathode is interchangeable with the filament type cathode and vice versa.

Thus, an electronic device has been described which does not depend solely on secondary electron emission, or thermionic emission but combines the useful characteristics of both. The combined application of secondary electron emission and thermionic emission makes the electronic oscillator and multiplier more stable, reliable, and cheaper to manufacture than those devices which rely solely on secondary emission.

I claim as my invention:

1. An electronic device of the character described comprising an evacuated envelope, an accelerating anode and a secondary emissive electrode mounted within said envelope and including an opening in its emissive surface, a primary electron emitting electrode located within and having an emissive surface flush with said opening, and means for energizing said additional electrode for the emission of primary electrons.

2. An electronic device of the character described comprising an evacuated envelope, an accelerating anode and a secondary emissive electrode mounted within said envelope and having an opening in its emissive surface, an additional electrode arranged within said opening and having a surface which is substantially in alignment with the emissive surface of said secondary emissive electrode and means for energizing said additional electrode for the emission of primary electrons.

3. An electronic device of the character described comprising an evacuated envelope, an accelerating anode and a secondary emissive electrode mounted within said envelope, said secondary emissive electrode having an opening in its emissive surface, and a unipotential cathode connected to said secondary emissive electrode and mounted within said opening having its emissive surface substantially flush with said emissive surface.

4. An electronic device of the character described comprising an evacuated envelope containing an accelerating anode, a pair of electrodes disposed on opposite sides of said anode

and having surfaces of secondary emissive material, one of said pair of electrodes having an opening within its emissive surface, and an additional electrode, arranged within said opening flush with one of said surfaces and made of a primary electron emitting material.

5. In a device of the character described by claim 1, a tunable circuit connected between said anode and secondary emissive electrode, a source 10 of electrical energy for biasing said anode positive with respect to said secondary emissive electrode, and a magnetic field for influencing electron movement within said envelope.

6. In a device of the character described by claim 4, means for energizing said additional electrode, a tunable circuit connected between said anode and secondary emissive electrodes, a source 20 of electrical energy for biasing said anode positive with respect to said secondary emissive electrodes, and a magnetic field for influencing electron movement within said envelope.

7. An electronic device of the character described comprising an evacuated envelope, an accelerating anode and a secondary emissive electrode mounted within said envelope, an additional electrode one of the surfaces of which is substantially in the plane of the emissive surface of said secondary emissive electrode and which may be energized to emit primary electrons, 30 means for energizing said additional electrode, a tunable circuit connected between said anode and secondary emissive electrode, a source of electrical energy for biasing said anode positive with respect to said secondary emissive electrode, 35 and a magnetic field for influencing electron movement within said envelope.

8. An electronic multiplier comprising an evacuated envelope, an accelerating anode of cylindrical form; a hollow cylindrical electrode surrounding said anode and having an inner surface of secondary electron emissive material; and a thermionic cathode connected to said hollow electrode and disposed substantially in alignment with said inner surface.

9. An electronic multiplier comprising an evacuated envelope, a pair of accelerating anodes of hollow cylindrical form; a pair of cylindrical electrodes mounted within said anodes and having outer surfaces of secondary emissive material; and a pair of thermionic cathodes connected to said pair of cylindrical electrodes and having electron emitting surfaces disposed substantially in alignment with said outer surfaces. 5

10. A device of the character of claim 8 including a magnetic field for influencing electron movement within said envelope, a source of power for energizing said cathode, a tunable circuit, a source of biasing voltage and serial connections between said anode, electrode, source of 15 biasing voltage, and tunable circuit.

11. A device of the character of claim 9 including a magnetic field for influencing electron movement within said envelope, a source of power for energizing said cathodes, a tunable circuit, 20 connections from said tunable circuit to said accelerating anodes, and a source of biasing voltage connected between a point intermediate the terminals of said tunable circuit and said electrodes. 25

12. An electronic device of the character described comprising an evacuated envelope, an accelerating anode and a secondary emissive electrode mounted within said envelope and having an opening in its emissive surface, an additional electrode mounted within said opening and having a surface which is substantially in alignment with the emissive surface of said secondary emissive electrode and which may be energized to emit primary electrons, means for 35 energizing said additional electrode, a tunable circuit connected between said anode and secondary emissive electrode, a source of electrical energy for biasing said anode positive with respect to said secondary emissive electrode, and a magnetic field for influencing electron movement 40 within said envelope.

ROBERT RHEA GOODRICH, 2ND.
